(57) **CLAIM**

The ornamental design for a water polo headgear, as shown and described.

DESCRIPTION

FIG. 1 is an upper perspective view of the water polo headgear;

FIG. 2 is a lower perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

A central part of the headgear forms a continuous padded section that is configured to cover a person's forehead, the top of the head, and the rear of a person's head.

The broken lines shown on the interior of the water polo headgear, which define the bounds of the claimed design, form no part thereof.
